HEATING SLEEVE FOR PERMANENT WAVES

Jean Leclabart, 53 Ave. Raymond Poincare, Paris, France

Filed Aug. 10, 1965, Ser. No. 86,516

Term of patent 14 years

(Cl. D86—10)

FIG. 1 is a perspective view of a heating sleeve for permanent waves showing my new design, the side opposite being identical thereto;

FIG. 2 is a cross sectional view on the line 2—2 of FIG. 1.

I claim:

The ornamental design for a heating sleeve for permanent waves, substantially as shown and described.
